[57] CLAIM

The ornamental design for an electro-magnet probe, as shown and described.

DESCRIPTION

FIG. 1 is a perspective view of the electro-magnetic probe showing my new design;

FIG. 2 is a fragmentary side elevational view thereof with the flexible cable portion being shown broken away for illustrative purposes only;

FIG. 3 is a left end elevational view thereof;

FIG. 4 is a right end elevational view thereof.

Fig. 2
